UNITED STATES PATENT OFFICE.

WALTER H. PERKINS, OF WATERBURY, CONNECTICUT, ASSIGNOR TO THE WATERBURY MFG. CO., OF WATERBURY, CONNECTICUT, A CORPORATION.

POWDER-BOX TOP.

No. 888,733.

Specification of Letters Patent.

Patented May 26, 1908.

Application filed November 11, 1907. Serial No. 401,726.

To all whom it may concern:

Be it known that I, WALTER H. PERKINS, a citizen of the United States, residing at Waterbury, in the county of New Haven and 5 State of Connecticut, have invented a new and useful Improvement in Powder-Box Tops; and I do hereby declare the following, when taken in connection with the accompanying drawings and the letters of reference 10 marked thereon, to be a full, clear, and exact description of the same, and which said drawings constitute part of this specification, and represent, in—

Figure 1 a side view of the upper portion of 15 a powder box constructed in accordance with my invention, the cover shown in closed position. Fig. 2 a side view of the same. Fig. 3 a top or plan view of the same with the cover shown in open position. Fig. 4 a trans- 20 verse sectional view on an enlarged scale.

This invention relates to an improvement in powder box tops, that is, boxes for toilet powder, and particularly to boxes which have a perforated top through which the 25 contents may be sifted, the object of the invention being a simple arrangement whereby the box is readily opened and tightly closed; and the invention consists in the construction hereinafter described and particularly recited 30 in the claim.

The box 2 may be of any approved design having a neck 3 and an integral top 4, this top having perforations 5 more or less in number, the upper part of the box, neck 3 and top 4 being drawn from a single piece of 35 metal and preferably an annular shoulder 6 will be formed around the upper edge of the

neck. Pivoted to the top 4 near the outer edge thereof is a cover 7 substantially in diameter to the diameter of the top 4 and having a downwardly projecting finger 8 which engages with the shoulder 6 when the cover is swung over the top.

In the center of the cover is a recess 9 in which is placed a packing 10 of paper, felt or other suitable material, which will closely fit upon the upper surface of the top 4 and so as to completely close the perforations 5. This cover is readily swung to one side as 45 shown in Fig. 3 of the drawings when it is desired to use the contents of the box, and when the cover is closed air is excluded from the contents of the box.

The cover, like the cap, is readily struck up from sheet metal and consequently a box 50 with its cover may be produced at a very low cost for manufacture.

I claim:

A powder box comprising a neck, an integral perforated top and formed with an annular shoulder around the upper edge of the neck, a cover pivoted to the top and formed with a downwardly projecting finger adapted to engage with the said shoulder, said cover also formed with a central recess and a piece 60 of packing material located therein.

In testimony whereof, I have signed this specification in the presence of two subscribing witnesses.

WALTER H. PERKINS.
